UNITED STATES PATENT OFFICE

WASHINGTON A. STOEHR, OF RESERVE TOWNSHIP, ALLEGHENY COUNTY, PENNSYLVANIA

CORNER ELEMENT FOR WALL-VENEERING MATERIAL

Original application filed October 2, 1926, Serial No. 139,120. Divided and this application filed September 22, 1928. Serial No. 307,619.

This application for Letters Patent is a division of application for Letters Patent Serial Number 139,120, filed by me in the United States Patent Office October 2nd, 1926. In my said pending application for Letters Patent I describe and claim new and improved wall-veneering material for the simulation of walls formed of assembled building blocks or units, such as brick, natural or artificial stone blocks, tile and the like.

In my present invention I provide elements suitable for forming the corners and ends of the veneered walls and for similar purposes, such, for instance, as for veneering pillars.

In the accompanying drawings, wherein I have illustrated the best embodiment of the principles of my invention now known to me, Fig. 1 is a view in perspective showing two of the corner elements in place on a backing wall.

Fig. 2 is a sectional view of the elements taken along the irregular line 2—2 in Fig. 1.

Fig. 3 is a perspective view of the lower element shown in Fig. 1.

Fig. 4 is a perspective view of the elements assembled to form the end of a wall.

Referring first to Figs. 1, 2 and 3 of the drawings, 1 and 2 represent the walls of a building or other structure which converge and join to form a corner, the same being shown in dotted lines.

The illustration is that of walls formed of vertical studding and horizontal boarding nailed thereto but it will be understood that any character of a wall may be veneered by means of my invention.

My improved corner elements are generally designated by the numeral 3, two of the same 3^a and 3^b being shown in assembled relation.

The structure of the corner elements is substantially as follows.

The body of the element is composed of a relatively thin backing plate 4, preferably of relatively flexible, waterproof material, such as asbestos board. The plates 4 are rectangular in shape and of angular form to correspond to the corner of the wall—usually substantially at right angles.

The lower portion of the plate 4 is provided with an outwardly protruding block portion 5 which is shaped and colored to represent a brick or other building unit.

The block 5, which is permanently fixed on the plate 4, is preferably of more rigid material than that of the plate 4, such as of a suitable cementitious material which will retain its conformation and will permanently adhere to the plate 4.

The two portions or wings of the plate 4 which are disposed in angular relation to each other are not of the same width, but one portion, the left hand wing in the case of the element 3^a in Figs. 1 and 3 and in the right hand wing in the case of the element 3^b in Fig. 1 is of sufficient width to provide room for the longer dimension or side face of a brick to be represented by the block 5 while the other wing of the plate is of proper width to provide room for the representation of the end of the brick.

Thus in the case of a superimposed series of elements the wider wing is disposed in alternate directions to break joints, as in brick, masonry and block-work.

The front or vertical faces of the block 5 is preferably not parallel with the general plane of the plate 4 but diverge upwardly therefrom at such an angle that when the elements are assembled against a vertical wall with their plates 4 overlapping each other from above, as shown in Figs. 1 and 2, the front faces of the blocks 5 will be vertically disposed or all in the same plane.

At one of the vertical edges of the plate 4, the right hand edge in the drawings, the block 5 is stepped back from the vertical edge of the plate to leave a relatively narrow vertical and sunken strip 6 which represents the vertical mortar bond between adjacent bricks or blocks in the same horizontal row. In brick work this strip is preferably about a half-inch in width. The plane of this strip 95 is preferably parallel with that of the front face of the block.

At the other vertical edge of the plate 4, the end of the block 5 is flush with the edge of the plate 4 so that the strip 6 will be disposed 100

between the two adjacent blocks in simulation of the mortar bond.

Again, the bottom of the block 5 is stepped upwardly from the bottom edge of the plate 4 to provide a horizontally disposed and sunk-en strip 7 representing the mortar bond between the block and the blocks in the next row below. The plane of this strip is also substantially parallel to that of the vertical face 10 of the block.

When the elements are assembled in superimposed and overlapping relation, as in Figs. 1 and 2, the bottom edge of the plate of the upper element 3^b will rest against the top surface 15 face of the blocks of the elements next below.

Likewise when two elements are placed side by side, as illustrated in Fig. 4, the vertical edges of the elements will abut together, the end of one block 5 being disposed at the outer 20 side of the vertical mortar strip 6 of the other element.

The inner edge of the strip 6 meets the end of the block 5 of the same element with a slight curve or fillet 8, just as the mortar bond 25 usually meets the brick, and at its outer edge a similar fillet 9 is provided to meet the block of the next adjacent element.

The mortar strip 7 which is at the lower edge of the plate 4 below the block 5 is provided with a fillet 10 which meets the block 5 of the same element and along its bottom edge the strip 7 is provided with a fillet 11 to meet the block or blocks next below.

The strips 6 and 7 are colored to represent 35 mortar or cement.

In assembling the elements to form a corner the elements 3^a and 3^b are alternated in vertical series, thus breaking joints and matching at their vertical edges with the wall elements which are the subject matter of my 40 above mentioned patent application.

In the case of the bottom element, illustrated at 3^a in Figs. 1 and 2, 1 provide an upwardly tapered filler block or blocks 12 45 inserted beneath the lower portion of the element between the latter and the wall to give the proper inclined position to the element to permit the overlapping of the superimposed elements.

50 The elements may be nailed in place to the walls by nails driven through the holes 13, the nails in each element being concealed by the elements superimposed thereon.

For the purpose of providing ventilation 55 and preventing the accumulation of dampness and the occurrence of rot, the top edge of each of the elements is provided with notches 14, preferably of arcuate shape into which merge the upper end of flutings 15 60 formed in the inner faces of the plate 4, said flutings being of sufficient length to partially overlap the notches of the elements next below, thus forming continuous air spaces between the veneering and the supporting wall.

65 The flutings are preferably of arcuate cross-

sectional shape and of upwardly increasing width and depth.

The nail holes 13 are preferably so positioned as to register with the notches 14 of elements next below so that a nail extends 70 through but one element only.

In Fig. 4 I show the method of assembling the corner units to form the end of a wall or a square pillar or the like, the elements 3^a and 3^b being alternated both horizontally and 75 vertically.

It is evident from the foregoing that my improved corner elements may be quickly and securely attached to a wall or building and that, when used in connection with my siding 80 elements which are the subject matter of my said application, a close simulation of a wall of brick, masonry, block and the like will be obtained.

What I desire to claim is:—

1. A wall veneering element for use at corners and comprising a backing plate in the form of two wings horizontally in angular relation to each other and the lower portion of the plate being provided with an outwardly extending block portion in simulation of a building unit, the block portion on the two wings of the plate representing two faces of a building unit disposed in angular relation to each other.

2. A wall veneering element for use at corners and comprising a backing plate in the form of two wings horizontally in angular relation to each other and of unequal widths and the lower portion of the plate being provided with an outwardly extending block portion in simulation of a building unit, the block portion on the wider wing of the plate representing the longer side of a building unit while the block portion on the narrower wing represents the narrower end of the unit.

3. A wall veneering element for use at corners and comprising a backing plate in the form of two wings horizontally in angular relation to each other and the lower portion of the plate being provided with an outwardly extending block portion in simulation of a building unit, the block portion on the two wings of the plate representing two faces of a building unit disposed in angular relation to each other, and there being provided along the bottom of the block portion a horizontal strip to represent the horizontal mortar bond between the block portions of superimposed elements.

4. A wall veneering element for use at corners and comprising a backing plate in the form of two wings horizontally in angular relation to each other and the lower portion of the plate being provided with an outwardly extending block portion in simulation of a building unit, the block portion on the two wings of the plate representing two faces of a building unit disposed in angular

relation to each other, and there being provided at one end of the block portion a vertical strip to represent the vertical mortar bond between the block portions of horizontally associated units.

5. A wall veneering element for use at corners and comprising a backing plate in the form of two wings horizontally in angular relation to each other and the lower portion of the plate being provided with an outwardly extending block portion in simulation of a building unit, the block portion on the two wings of the plate representing two faces of a building unit disposed in angular relation to each other, and there being provided along the bottom of the block portion a horizontal strip to represent the horizontal mortar bond between the block portions of superimposed elements and there being also provided at one end of the block portion a vertical strip to represent the vertical mortar bond between the block portions of horizontally associated elements.

6. A wall veneer corner structure comprising a plurality of elements in downwardly overlapping relation, and each element comprising a backing plate in the form of two wings horizontally in angular relation to each other and the lower portion of the plate being provided with an outwardly extending block portion in simulation of a building unit, the block portions on the two wings of the plate representing the two faces of a building unit disposed in angular relation to each other, the elements being overlapped in assembling so that the lower edge of a superimposed element impinges on the upper face of the block portion of the element next below.

40 7. A wall veneer corner structure comprising a plurality of elements in downwardly overlapping relation, and each element comprising a backing plate in the form of two wings horizontally in angular relation to each other and the lower portion of the plate being provided with an outwardly extending block portion in simulation of a building unit, the block portions on the two wings of the plate representing the two faces of a building unit disposed in angular relation to each other, the elements being overlapped in assembling so that the lower edge of a superimposed element impinges on the upper face of the block portion of the element next below, and the plates being provided with horizontal strips to represent the mortar bond between block portions of the elements.

8. A wall veneer corner structure comprising a plurality of elements in downwardly overlapping relation, and each element comprising a backing plate in the form of two wings horizontally in angular relation to each other and the lower portion of the plate being provided with an outwardly extending block portion in simulation of a building

unit, the block portions on the two wings of the plate representing the two faces of a building unit disposed in angular relation to each other, the elements being overlapped in assembling so that the lower edge of a superimposed element impinges on the upper face of the block portion of the element next below, the plates being provided with horizontal strips to represent the mortar bond between block portions of the elements, and there being provided at one end of the block portion of an element a strip to represent the vertical mortar bond between said block portion and the block portion of a horizontally adjacent element.

9. A wall veneer corner structure comprising a plurality of elements in downwardly overlapping relation, and each element comprising a backing plate in the form of two wings of unequal width and horizontally in angular relation to each other and the lower portion of the plate being provided with an outwardly extending block portion in simulation of a building unit, the block portion on the wider wing representing the longer side of a building unit while the block portion on the narrower wing represents the narrower end of the building unit, the elements being overlapped with the lower edge of an upper element impinging on the upper face of the block portion of the element next below, and alternate units having their wider wings disposed on opposite sides of the corner.

10. A wall veneer corner structure comprising a plurality of elements in downwardly overlapping relation, and each element comprising a backing plate in the form of two wings of unequal width and horizontally in angular relation to each other and the lower portion of the plate being provided with an outwardly extending block portion in simulation of a building unit, the block portion on the wider wing representing the longer side of a building unit while the block portion on the narrower wing represents the narrower end of the building unit, the elements being overlapped with the lower edge of an upper element impinging on the upper face of the block portion of the element next below, and alternate units having their wider wings disposed on opposite sides of the corner, and the plates being provided with horizontal strips which represent the horizontal mortar bond between the block portion of overlapping plates.

11. A wall veneer corner structure comprising a plurality of elements in downwardly overlapping relation, and each element comprising a backing plate in the form of two wings of unequal width and horizontally in angular relation to each other and the lower portion of the plate being provided with an outwardly extending block portion in simulation of a building unit, the block

portion on the wider wing representing the longer side of a building unit while the block portion on the narrower wing represents the narrower end of the building unit, the elements being overlapped with the lower edge of an upper element impinging on the upper face of the block portion of the element next below, and alternate units having their wider wings disposed on opposite sides of the corner, and there also being provided at one end of the block portion of an element a narrow vertical strip to represent the vertical mortar bond between the block portions of horizontally adjacent elements.

15 Signed at Pittsburgh, Pa., this 20th day of Sept. 1928.
